Primary Examiner—T. Chase Nelson*Assistant Examiner*—Karen Acker(74) *Attorney, Agent, or Firm*—Whyte Hirschboeck Dudek SC(57) **CLAIM**

The ornamental design for imitation rattan strip, as shown and described.

DESCRIPTION

FIG. 1 is a perspective view of imitation rattan strip showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The design is shown broken away in order to show that a specific length of imitation rattan strip forms no part of the claimed design.

The broken lines are included for the purpose of illustration only and form no part of the claimed design.
